(57) **CLAIM**

The ornamental design of a furniture glide, as shown and described.

DESCRIPTION

FIG. 1 is an isometric view of a furniture glide in accordance with the present invention;

FIG. 2 is a top plan view of the furniture glide of FIG. 1; FIG. 3 is a side elevational view of the furniture glide of FIG. 1;

FIG. 4 is a bottom plan view of the furniture glide of FIG. 1; and,

FIG. 5 is a cross-sectional view of the furniture glide of the present invention taken along line 5—5 of FIG. 2 showing, in phantom, adhesive and a backing for the adhesive affixed to the bottom surface of the furniture glide shown for illustrative purposes only and forming no part of the claimed design.
